(57) **CLAIM**

The ornamental design for an ear plug, as shown and described.

DESCRIPTION

1. Ear plug
Figure 1.1 is a perspective view of an ear plug;
Figure 1.2 is a front view thereof;
Figure 1.3 is a left side view thereof;
Figure 1.4 is a back side view thereof;
Figure 1.5 is a right view thereof;
Figure 1.6 is a top view thereof;
Figure 1.7 is a bottom view thereof; and
Figure 1.8 is another perspective view thereof.

(Continued)

The broken lines shown in Figures **1.4**, **1.5**, **1.6** and **1.8** illustrate portions of the ear plug that form no part of the claimed design.
